Primary Examiner — Cynthia Ramirez(74) Attorney, Agent, or Firm — Howard & Howard Attorneys PLLC(57) CLAIM

The ornamental design for a liner for a grocery cart, as shown and described.

DESCRIPTION

FIG. 1 is front perspective view of a liner for a grocery cart showing our new design;

FIG. 2 is a rear perspective view of the liner from FIG. 1;

FIG. 3 is an elevational view of the liner from FIGS. 1 and 2;

FIG. 4 is a top plan view of the liner from FIGS. 1-3;

FIG. 5 is an opposite side elevational view of the liner from FIG. 3; and,

FIG. 6 is a bottom plan view of the liner from FIGS. 1-5.

The dash-dot-dot lines in the figures are for the purpose of illustrating environment only and form no part of the claimed design.
